UNITED STATES PATENT OFFICE.

MATTHEW H. MERRIAM, OF LEXINGTON, MASSACHUSETTS.

NOTCHING DEVICE FOR PIPING.

SPECIFICATION forming part of Letters Patent No. 270,967, dated January 23, 1883.

Application filed November 20, 1882. (No model.)

To all whom it may concern:

Be it known that I, MATTHEW H. MERRIAM, of Lexington, county of Middlesex, and State of Massachusetts, have invented an Improvement in Notching Devices for Piping, of which the following description, in connection with the accompanying drawings, is a specification, like letters on the drawings representing like parts.

- 10 When leather piping such as is commonly inserted between layers of leather to form an edge-finish is to be bent to finish square corners it is essential for good work that the inner or unfinished edge of the piping, which is placed between the layers of leather, be notched exactly opposite the corner to enable the piping to be bent at the proper place. To facilitate bending the piping, its inner edge has been provided with a series of V-shaped notches; but this does not always answer the purpose, for it often happens that the notch does not come in just the proper position with relation to the corner to be finished, and hence good and even work cannot be done. In accordance with my plan the piping may be left straight or uncut at its inner edge, and when the piping being applied by stitches arrives at a corner where the piping is to be bent the operator places under the piping the thin end of one member of the notching device herein described, and moves the other member of the said device down upon the piping, and removes a triangular piece of material from its inner edge at the exact point where the bend is to be made. After this the piping may be bent at just the proper point to be shaped to the corner to be finished.
- 20 Figure 1 represents in side elevation a notching-device embodying my invention;
- 25 Fig. 2, a plan of the die part of the under jaw;
- 30 Fig. 3, a view of the punching part of the up-

per jaw; and Fig. 4 shows a piece of material being finished by piping.

My notching device is composed of two jaws, *a* and *b*. Jaw *a* is provided with a thin blade, *a'*, which may be readily inserted between the piping and the bed-plate of the sewing-machine, the needle and other parts of which are being employed to stitch the piping *d*, between two pieces of leather, *e*. Jaw *b* is provided with a punch or male part, *b'*. Let it be supposed that a piece of piping *d* is being inserted between the edges of two layers of leather *e*, and is being stitched between the said layers by a row of sewing-machine stitches at *g*.

When corners such as shown at *h i* are to be finished or piped, the piping, when immediately opposite the said corners, may be notched by introducing the long, thin die *a'* under the said piping and then causing the jaw *b* and punch *b'* to be moved or shut down upon the piping, cutting out or notching its inner edge, as at 2, Fig. 4, thus enabling the piping to be bent at just the proper spot.

The long, thin jaw may be inserted under the piping without disturbing it as to its relation to the sewing parts, and without affecting the continuity of the succession of stitches.

I claim—

The notching device composed of the jaw *a*, provided with a thin plate or nose, having the die-opening *c*, combined with the jaw *b*, provided with the punch *b'*, to operate all substantially as shown and described.

In testimony whereof I have signed my name to this specification in presence of two subscribing witnesses.

MATTHEW H. MERRIAM.
